CLAIM

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with graphical user interface showing an embodiment of our new design;

FIG. 2 is a front view of a display screen with graphical user interface showing an embodiment of our new design;

FIG. 3 is a front view of a display screen with graphical user interface showing an embodiment of our new design;

FIG. 4 is a front view of a display screen with graphical user interface showing an embodiment of our new design;

FIG. 5 is a front view of a display screen with graphical user interface showing an embodiment of our new design; and,

FIG. 6 is a front view of a display screen with graphical user interface showing an embodiment of our new design.

In the drawings, the broken lines are for the purpose of illustrating the display screen and a portion of the graphical user interface and forms no part of the claimed design.
